UNITED STATES PATENT OFFICE.

MICHAEL J. WHELAN, OF MUSKEGON, MICHIGAN, ASSIGNOR TO BRUNSWICK-BALKE-COLLENDER CO., A CORPORATION OF DELAWARE.

CLOSET-SEAT.

1,273,703.

Specification of Letters Patent. Patented July 23, 1918.

Application filed January 5, 1914. Serial No. 810,476.

To all whom it may concern:

Be it known that I, MICHAEL J. WHELAN, a citizen of the United States, and a resident of the city of Muskegon, in the county of Muskegon and State of Michigan, have invented certain new and useful Improvements in Closet-Seats; and I do hereby declare that the following description of my said invention, taken in connection with the accompanying sheet of drawings, forms a full, clear, and exact specification, which will enable others skilled in the art to which it appertains to make and use the same.

This invention relates generally to improvements in closet seats, and it consists, essentially, in the novel and peculiar combination of parts and details of construction, as hereinafter first fully set forth and described and then pointed out in the claim. In the drawing already referred to, which serves to illustrate my said invention more fully, Figure 1 is a plan of a rectangular wood blank,—parts being broken away to show the several layers of veneer comprising said blank. Fig. 2 is a section in line 2—2 of Fig. 1. Fig. 3 is a plan of the said blank sawn to approximate outline to produce the core of a water closet seat comprising my invention. Fig. 4 is a plan of the blank after being machined and turned to produce the seat core, said plan showing pubescent surfaces produced in the process of machining for purposes hereinafter described. Fig. 5 is a cross section in line 5—5 of Fig. 4 on an enlarged scale. Fig. 6 is a section in line 6—6 of Fig. 4 on an enlarged scale, showing the same as being covered with a fine, hard rubber veneer. Fig. 7 is a similar cross section illustrating a seat having a concavo-convex cross section, this conformation being preferred when an especially light weight seat is a desideratum.

Like parts are designated by corresponding symbols or characters of reference in all the figures of the drawings.

One of the greatest sanitary necessities of the present day, particularly and especially with respect to public comfort stations, hotel and public toilet rooms, and, in fact private bath rooms, are water closet seats which are unbreakable and sanitary in every respect; seats in which there are no crevices of any kind for the reception of germ generating matter, and whose outer surfaces are

positively immune from germ impregnation. Such seats, to be a success, must always remain "sweet" and must be of such a nature that fecal matter deposited thereon may easily be removed therefrom without affecting the outer finish thereof.

The only material which possesses the qualities of not being affected by moisture, the action of uric acids, or excrementitious matter is fine, hard rubber. But, a seat made from this material, while being ideal for the purpose specified, is prohibitive in cost.

Therefore, the object of my invention is the construction of a sanitary water closet seat in which all the preëminent qualities of a fine, hard rubber seat are retained, which is capable of as high a polish, and is as able to retain the same under service, at a price which will enable it to be sold in competition with the average types of wooden seats.

To secure this result I prepare a wooden blank B which is built up from a plurality of layers of sheared wood veneer 1, 2, 3, 4, and 5. This veneer averages about $\frac{1}{8}$ " thick and is of the cheapest grade of lumber, such as gum wood, cotton wood, bass wood, and the like. These sheets of veneer are sawn to rectangular outline of a size that a seat blank may be sawn therefrom, and every sheet is first kiln dried, after which I apply a thin layer of heat and moisture proof glue or cement to each sheet and build up the blank B, the grain of each successive sheet being disposed angularly to the grain of the preceding sheet as clearly seen at 6, 7, 8, 9, and 10, Fig. 1. After the blank is built up, the same is placed in a suitable press and the layers of veneer comprising the same squeezed together under great pressure, so as to secure perfect contact of all the surfaces with the cement. After the cement is set, the completed blank is again placed in a drying kiln under pressure and so super-kiln dried that the last vestige of moisture has been expelled therefrom.

The blank B is next sawn to an outline approximately the external contour of, though somewhat larger all around than, a finished seat, producing a semi-shaped blank B', Fig. 3. Said blank B' is then placed in a suitable shape turning lathe and the shaped seat-core C produced. This core is not smoothly finished, on the contrary the shape of the turning tool and the feed

thereof is such as to produce a pubescent surface D throughout the surfaces of the core, leaving the same with a rough, grooved, pubescent surface. Said core is machined 5 somewhat smaller than the finished seat is to be, and is now ready for its exterior veneer of fine hard rubber.

It will now be observed that the core being built up in layers, of wood veneer, the grain 10 of each successive layer of which is disposed angularly of the grain of the preceding layer, the whole so thoroughly kiln dried as to be devoid of moisture, a seat core is produced which is as near unbreakable as 15 it is possible to manufacture such an article. And combined with this there is a lightness of weight not otherwise obtainable.

A sheet of semi-plastic fine rubber is now pressed into shape in a proper mold, and the 20 aforesaid core is placed within said sheet, with a flat sheet of semi-plastic fine rubber placed over the core. The mold is closed, placed in a press and great pressure applied, forcing the semi-plastic fine rubber veneer 25 directly into the faces of the core and causing the rubber material to become anchored, as it were, to the pubescent surface hereinbefore mentioned, thereby causing a double adhesion of the rubber veneer to the core. 30 The next process is the placing of the filled mold into a vulcanizer, whereby suitable curing under heat and pressure, the semi-plastic fine rubber is converted into a true vulcanite or hard rubber veneer E, dense 35 and hard in texture, hermetically sealed within which is the wooden core C above described.

So great is the adhesion of this hard rubber veneer to the core that if the seat be 40 smashed by means of an ax or like instrument the vulcanite will be found to adhere to the splinters into which the core may be chopped. To all intents and purposes the rubber veneer and veneered or laminated 45 wood core are an integral mass, and this is due to the following causes; First, the thorough kiln drying of the core, as described,

renders the fiber of the core more easy of penetration by the semi-plastic rubber veneer, and secondly, the pubescent surface of 50 the core proves an additional anchorage for the rubber.

The forcing of the rubber in a plastic or semi-plastic state upon the roughened exterior surface forms an integral bond which 55 inseparably joins the surfaces of the inner and outer portions of the seat to each other, and which is composed of a multiplicity of interfitted minute projections on the contacting surfaces homogeneously united to 60 each other by the vulcanization of the rubber.

I have not shown the seat cover employed, as the same is of like construction as the seat, but minus the opening O. Neither 65 have I illustrated the seat hinges and rubber buffers, as they are of typical construction and are not part of my invention.

It is now to be understood that I may produce my seat in any desired or preferred 70 shape or conformation.

Having thus fully described my invention, I claim as new and desire to secure to myself by Letters Patent of the United States:—

A closet seat comprising a wood core consisting of a plurality of thoroughly dried layers of wood veneer arranged one upon the other with the grain of each layer disposed angularly with respect to the grain of 80 the adjacent layer or layers, said layers being cemented together and said core having a rough pubescent surface, and a covering of hard rubber vulcanized on said core and united therewith throughout the entire surface of the core.

In testimony whereof I have hereunto set my hand in the presence of two subscribing witnesses.

MICHAEL J. WHELAN.
